UNITED STATES PATENT OFFICE.

JOHN WILLIAM SUTCLIFFE, OF LONDON, ENGLAND.

METHOD OF SEALING JARS AND THE LIKE CONTAINERS AND IMPROVED SEALING CAPSULE THEREFOR.

Application filed November 23, 1925, Serial No. 70,916, and in Great Britain November 29, 1924.

The present invention relates to an improved closure for the sealing of jars, bottles and the like.

It has been usual to seal a cap on a jar or 5 bottle by means of a flanged sealing strip or band which is applied to the jar or bottle with the cap or stopper and previous to having its lower edge spun to form an inturned flange bearing below a flange on the jar or 10 bottle.

The spinning under of the edge of this strip in this manner has had certain disadvantages in that considerable force was necessary, so that where it was not always 15 possible to arrange for the flange on the bottle or jar to be accurately disposed at right angles to the axis of the bottle or jar, or to an accurate depth from the top of the bottle or jar, it occurred that the sealing or 20 spinning tools have caused a cracking and breakage of this flange, and again in other cases the metal of the band was apt to pucker so that the band could not form a proper seal.

According to the present invention the 25 lower edge alone of a sealing strip or band for applying to the closure cap or stopper of a jar or bottle has its structure weakened so that it may subsequently readily bend 30 substantially at right angles to the band by the use of moderate pressure. This weakening of structure may be for instance, effected by grooving the band adjacent the line along which it will be bent inwards, or 35 again by removing the portions from the band adjacent its edge, either by perforating the band adjacent the edge or by serrating this edge, so that in each case the edge can be bent inwards by moderate pressure, which otherwise would be only possible by causing the metal to distort, which as can be readily seen, requires considerable 40 mechanical force.

The invention is more particularly de- 45 scribed with reference to the accompanying drawings, in which:—

Figure 1 is a part elevation of a bottle with an improved closure in place upon it shown in section.

Figure 2 is a corresponding view to Figure 1 showing the sealing strip or band only developed in elevation.

Figures 3 and 4 show modified forms of sealing band.

Figure 5 shows the form of band or strip

of Figure 2 ready for application to a jar.

Figure 6 is a view showing the crimped edge of the band of Figure 5 after sealing.

Figure 7 is a diagrammatic view of the action of an elastic sealing element on the 60 lower edge of the strip or band.

Figure 8 is a modified form of closure in sectional elevation.

Figures 9 to 11 show a modified fastening for the ends of the strip. 65

A bottle 1, has, as is usual with certain forms of closure, a closure cap 4, which has an elastic ring of rubber, cork or the like 5, which is pressed hermetically upon the upper flange surface 6 of the bottle or jar 1. 70 After the jar has been filled with its contents and the cap 4 applied, the sealing strip or band of the present invention is then applied. This sealing strip or band 7 has the usual upper inturned flange 8, but has its 75 lower edge 9 weakened by perforating as shown in Figures 3 and 4.

The perforations may be rectangular as shown in Figure 3, circular as shown in Figure 4, or any other convenient shape. 80

In the modified form of sealing band or strip shown in Figures 2, and 5 the strip is grooved peripherally at 14, prior to application to the jar. This grooving forms a fold which facilitates the crimping of this 85 lower edge of the strip under the flange on the jar as shown in Figure 5.

An important advantage of the sealing bands or strips of this invention is that the seal may be applied by a contracting pres- 90 sure applied simultaneously around the whole periphery of the strip when encircling the jar as the lower edge of the strip being weakened for instance by a grooving adjacent its edge, allows this to be deformed 95 without distortion, a process which requires considerably less effort than the turning in of a solid edged strip by spinning which in consequence of the reduction in peripheral length of the edge necessitates a flow 100 of the metal with consequent distortion of the strip edge.

In the case where the band or strip is grooved, this has the further advantage of strengthening the band laterally. 105

Further as shown diagrammatically in Figure 7 an elastic contracting sealing tool 15 will roll the lower depending edge 16 of the said strip around and under the edge 17 of the flange on the bottle or jar, the 110

grooving forming also an elastic and accommodating hinge line, thereby obviating any risk of breakage or damage to the flange 6 on the jar.

- 5 It has been found that this sealing strip or band provides a very effective closure for the reason that the sealing pressure is distributed evenly over a very large number of points around the flange ring on the jar
- 10 which overcomes the disadvantage present with the usual straight edge, in that this was apt to pucker or fold. Further, it is now possible to apply this closing strip by means of a spiral metal wire, a rubber or
- 15 other annular elastic die so that any irregularity in the flange on the glass jar or bottle would be compensated for and owing to the elastic pressure there is no danger of splintering the glass.
- 20 The sealing element may either be in the form of a strip as shown, having detachable tongue and slot connections 12, 13 at its ends, or may be in the form of one piece ring.
- 25 The sealing elements can be formed from metal strip by cutting off to length, and punching the tongue and slot connections 12, 13. The upper flange can then be formed or may be formed simultaneously with the
- 30 above operations. The weakening of the lower edge by grooving, or by serration or perforations may be effected prior to cutting to length or simultaneously with the punching of the connection 12, 13.
- 35 A simple form of closure is shown in Figure 9 in which a bottle or jar 18 has an elastic washer 21 bearing on its neck 22. A disc or cap 23 of paper, collodion or other suitable material is slipped over it, the lower
- 40 edge of which cap 23 being held under the flange 24 of the bottle or jar by the closure ring flange 25. This forms a very effective seal.

Instead of forming a closure ring from a strip by interlocking tongue and slot means as shown in Figures 1 to 5 it will be found sufficient for many purposes to provide an undercut indentation or notch 26 in one end of the strip to interlock with a turned up

lip 27 on the other end of the strip. Or again as shown in Figures 10—11 the ends of the strip can be provided with interlocking dovetailing portions 28, 29 or again 30, 31, respectively which will be mutually engaged to form the strip into a ring prior to its application to the jar.

I declare that what I claim is:

1. A closure for containers comprising an elastic sealing element for the neck of the container, a metal ring embracing said neck, a flange on said ring bearing on the sealing element, and a lower rim on said ring having an unbroken lower edge and weakened peripherally along and above said edge. 60

2. As an article of manufacture a metal sealing element for containers comprising a metal strip having an upper flange and a lower rim having an unbroken lower edge and weakened peripherally along and above its edge. 65

3. A closure for containers comprising an elastic sealing element for the neck of the container, a metal strip embracing said neck, mutually engaging portions on the ends of said strip, a flange on said strip bearing on the sealing element, and a lower rim on said strip having an unbroken lower edge and weakened peripherally above and along said edge. 75

4. A closure for containers comprising an elastic sealing element for the neck of the container, a metal strip embracing said neck, mutually engaging portions on the ends of said strip, a flange on said strip bearing on the sealing element and a lower rim on said ring having an unbroken lower edge and an internal groove along and above its edge. 80

5. As an article of manufacture a metal sealing element for containers comprising a metal strip having an upper flange, mutually engaging portions at its ends and a lower rim having an unbroken lower edge and an internal groove along and above its lower edge. 85

In witness whereof, I have hereunto signed my name this 29th day of October, 1925.

JOHN WILLIAM SUTCLIFFE.
